UNITED STATES PATENT OFFICE

2,598,828

TRACK LINK

Alva W. Phelps, Kenilworth, Ill., assignor to The
Oliver Corporation, a corporation of Delaware

Application November 9, 1949, Serial No. 126,415

1 Claim. (Cl. 305—10)

1

The present invention relates generally to crawler type tractors, but more particularly to a novel and improved construction of the link which forms the endless track for crawler type tractors.

One of the primary objects of the present invention is to provide a novel, simple and easily assembled track link for crawler type tractors in which the link consists of two identical sections, except that one is a right hand section and the other is a left hand section, both of which are secured together by a single bolt to form the track link.

Another object of the invention is to provide a novel sectional track link in which the lug or tooth of the link is located in the approximate center of the track link and has a transverse bore therein to receive a bolt for securing the two sections together. In this connection it is to be noted that the lug or tooth portion of the link forms the sprocket wheel engaging surface at a position spaced from the pivotal connection with the adjacent links.

A still further object of the invention is to provide a novel and improved track link in the form of two sections secured together by a single bolt and in which the pivotal connection between the adjacent link is completely enclosed or sealed to prevent the entrance of abrasive soil into the bearing portions of said links.

Another object of the invention is to provide a novel and simplified sectional track link in which the pivotal connection between the adjacent links is properly sealed by a plastic or rubber ring for preventing the entrance of abrasive soil at points adjacent the inner pivotal connections or bearings between the links.

These and other objects are accomplished by providing a construction and an arrangement of the various parts in the manner hereinafter described and particularly pointed out in the appended claim.

Referring to the drawings:

Fig. 1 is an inside top plan view of a portion of a track embodying my improved track link;

Fig. 2 is a side elevational view of the same;

Fig. 3 is an end elevational view of one end of the track link;

Fig. 4 is an end elevational view of the other end of the track link;

Fig. 5 is a top plan or outside view of a portion of the track;

Fig. 6 is a cross sectional view taken on the line 6—6 in Fig. 1;

Fig. 7 is a cross sectional view taken on the line 7—7 in Fig. 2; and

2

Fig. 8 is a cross sectional view taken on the line 8—8 in Fig. 2.

In illustrating one form my improved track link may assume in practice, I have shown the same as comprising two identical track link sections, generally indicated by the reference character 10. The only difference between these two track link sections is that one is a right hand section while the other is a left hand section. 10 The track section in this instance comprises a flat horizontal ground engaging plate or base 11 of substantially rectangular shape and a perpendicular and upwardly extending side wall or rib 12 formed integrally therewith. The wall 12 15 of the track link section 10 is located in substantially the longitudinal center thereof. The inner and lower portions of the wall 12 are vertical, as shown at 13, and taper outwardly, as shown at 14. Formed integrally adjacent one end of the wall 12 20 is an outwardly projecting tapered bearing stud 15 which forms one of the pivotal connections to the next adjacent link in the manner hereinafter described. The other end of the vertical rib 12 of the link 10 is provided with an 25 outwardly offset or laterally projecting portion as shown at 16 which terminates in a longitudinal extension rib 17 in alignment with the outside edge 18 of the flat plate 11 of the track link section 10. Formed in this extension rib 17 is an 30 inside tapered socket 19 which is adapted to pivotally receive the complementary bearing stud 15 of the next adjacent link section. The socket 19 is completely enclosed from the outside by an offset wall 20 formed integrally with the wall extension 17 so as to prevent the entrance of 35 abrasive materials into the bearing portion of the link. The offset portion 16 of the track link section 10 is reinforced or strengthened by a horizontal rib 21 which is formed integrally with the track section and located at a point in approximate center of the track link section. The rib extension 17 has an irregular curved or cut-out 40 recess 22 on the inner side thereof so as to allow for sufficient clearance for the outwardly beveled end 23 of the next adjacent link on the pivotal movement of one link with the next adjacent link. The opposite ends of the plate 11 of the track link section 10 terminates short of planes 45 passing through pivotal points of the link sections, as shown at 23, so as to permit the discharge of accumulated soil or dirt between the adjacent link sections. Located in the longitudinal center of the track link section 10 and formed integrally 50 with the vertical rib 12 and plate 11 is an inwardly projecting lug or tooth 24. The outer surfaces 55

of this tooth 24 is engaged by the drive sprocket wheel teeth of the tractor. The opposite side walls of the tooth 24 may be in the form of involute curves to conform to similar curves of the sprocket wheel teeth. Located in transverse aligned bores 25 in the lugs 24 of the opposite sections 10 is a bolt 26 for securing the right and left hand track link sections 10 together. In this connection it will be noted that the inner longitudinal and contiguous vertical surfaces of the lugs 24 and horizontal plates 11 are machine finished as shown at 27 so that the right and left track link sections will be brought into proper alignment with one another in forming the complete link. In the drawings I have shown a single transverse and outwardly projecting tapered ground engaging lug 28, but it will, of course, be understood that other types or forms of ground engaging lugs may be formed integrally with the horizontal plate 11 of the track link sections 10.

In order to prevent the entrance of abrasive or foreign material into the bearing points of the adjacent links, I have provided a plastic or rubber ring 29 which is adapted to be seated in a semi-circular annular recess 30 on the inner end of the bearing stud 15. An annular curved recess 31 formed on the inner side of the rib extension 17 adjacent the periphery of the socket 19 engages the rubber ring 29 to seal the bearing at this point.

Summarizing the novel features and functions of operation of my improved track link, it will be understood that each track link consists of two identical link sections except that they are made up for right and left hand members in which a single bolt through the center of the sections secures the two sections together to form the link. In this connection it will also be observed that when one link is being connected to the next adjacent link, the bearing studs 15 are inserted in the complementary recesses 19 of the next adjacent link after which the bolt 26 may be inserted and secured. It will further be noted that by having the teeth of the drive sprocket wheel engage the intermediate portion of the track link at points spaced from the pivotal connections of the links, the driving strain is more evenly distributed throughout the link and at a point where the bolt securing the link sections together affords

additional strength. It will be further observed that by encasing the pivotal points on the outside of the link sections and sealing the inner portion of these bearings by a plastic or rubber seal ring, abrasive materials will be prevented from entering these bearing points to thereby reduce to a minimum the wear on these links and consequently reduce to a minimum the repair or replacement required.

While in the above specification I have described one embodiment which my invention may assume in practice, it will, of course, be understood that the same is capable of modification and that modification may be made without departing from the spirit and scope of the invention as expressed in the following claim.

What I claim as my invention and desire to secure by Letters Patent is:

An endless belt track link comprising two longitudinally extending right and left hand sections having contiguous inner finish surfaces contacting one another, said sections including horizontal flat plates and longitudinally extending perpendicular ribs spaced outwardly from the finished surfaces thereof, aligned and outwardly projecting studs formed on one end of said ribs, aligned bearing portions formed on the other ends of said ribs, there being aligned sockets in said bearing portions, walls formed integrally with said ribs and encasing the outer portions of said sockets, aligned drive wheel engaging lugs formed on said sections in the approximate center of said sections, there being aligned apertures in said lugs, and a bolt extending through said apertures for securing said sections together.

ALVA W. PHELPS.
